HAIR BRUSH

Harold Leighton, Apt. 15, St. John's Wood Court, St. John's Wood Road, London N.W. 8, England

Filed Aug. 3, 1973, Ser. No. 385,253

Claims priority, application Great Britain Feb. 8, 1973

Term of patent 14 years

Int. Cl. D4—02

U.S. Cl. D4—31

FIG. 1

FIG. 2

FIG. 3

FIG. 4

FIG. 1 is a side elevation of a hair brush showing my new design, the opposite side being identical thereto;

FIG. 2 is a top plan view thereof, the bottom plan view being identical thereto;

FIG. 3 is an end elevation of the hair brush viewed from the left of FIGS. 1 and 2; and

FIG. 4 is another end elevation of the hair brush viewed from the right of FIGS. 1 and 2.

I claim:

The ornamental design for a hair brush, substantially as shown and described.
